UNITED STATES PATENT OFFICE.

GEORGE L. McDERMOTT, OF DENVER, COLORADO.

PUMP.

1,164,831.

Specification of Letters Patent. Patented Dec. 21, 1915.

Application filed September 24, 1913. Serial No. 791,478.

To all whom it may concern:

Be it known that I, GEORGE L. McDERMOTT, a citizen of the United States, residing in the city and county of Denver and State of Colorado, have invented certain new and useful Improvements in Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in force pumps, my improved construction being more especially adapted for use where a plurality of cylinders are employed.

An important feature of my improved 20 construction lies in the special construction and arrangement of the valve, the operation of the latter and the construction of its seat, which is equipped with ports respectively in communication with the several cylinders 25 with which the pump is provided. The valve is provided with a single suction port and a single discharge port. There is a single passage leading from each cylinder to one of the ports of the valve seat, the latter being stationary. These passages become alternately suction and discharge passages and, through the medium of the ports in the valve seat, are alternately brought 30 into communication with the suction and discharge ports of the valve. The valve is 35 operated from the crank shaft of the pump, whereby rotary movement is imparted thereto and its action brought into synchronism with the movement of the pump plungers, 40 the operation of the valve and the movement of these plungers being properly timed to cause the discharge and suction ports of the valve to be successively and alternately brought into communication with the ports 45 of the valve seat. The construction is so arranged that the suction and discharge ports of the valve overlap the ports of the valve seat so that before the suction or discharge ceases through one port of the valve seat, 50 it commences through another port of the valve seat, whereby the discharge of fluid is

continuous. It will thus be seen that through the instrumentality of a single valve the suction and discharge to and from the pump cylinders is accomplished, the operation of the coöperating ports being properly timed for the purpose. It will also be observed that the construction is exceedingly simple, very effective and economical in operation. It is also compact, which is an important feature, as it is adapted to occupy 55 comparatively small space, considering its capacity.

In order to minimize the cost of repair, the valve and its seat are each equipped with 60 a wearing plate or disk which may be discarded, and a new one substituted at a very small cost, thus virtually renewing the valve and its seat.

Having briefly outlined my improved construction, I will proceed to describe the same in detail, reference being made to the accompanying drawing, in which is illustrated 70 an embodiment thereof.

In this drawing—Figure 1 is a vertical 75 section taken through my improved pump, cutting the cylinders longitudinally. Fig. 2 is a horizontal section taken through the structure on the line 2—2, Fig. 1, cutting the cylinders just above their bottom ports and 80 the valve casing just above the seat. Fig. 3 is a sectional detail view of the valve, taken through its two ports. Fig. 4 is a perspective view of the valve. Fig. 5 is an underneath view of the valve, or a view looking in 85 the direction of arrow 5, Fig. 3. Fig. 6 is a detail view of the wearing disk or plate which is applied to the bottom of the valve when the parts are assembled. Fig. 7 is a similar wearing disk or plate secured to the 90 valve seat. Fig. 8 is a detail view of the valve mechanism substantially identical with that shown in Fig. 1 except that the valve is shown in a different relative position.

The same reference characters indicate the 95 same parts in all the views.

Let the numeral 5 designate the framework of the pump which as illustrated, consists of a solid casting containing three cylinders 2, 3 and 4, equipped with plungers 7 100 connected by means of pitmen 8 with the cranks 9 of a crank shaft 10, having a pulley

12 for operating purposes. The extremity of the crank shaft opposite that where the pulley 12 is located is provided with a bevel gear 13 meshing with a similar gear 14 fast 5 on a shaft 15 to whose lower extremity is secured as shown at 16, a rotary valve 17, the latter being provided with a suction port 18 and a discharge port 19. The shaft or valve stem 15 passes through a stuffing box 20 mounted on a housing 21 arranged above the valve casing 22 and provided with an outlet port 23 for the water, air or other fluid with which the pump is employed.

As shown in the drawing, the discharge 15 port 19 extends through the valve from top to bottom and in cross sectional area it is curved to conform to the curvature of the outer surface of the valve. The suction port of the valve as shown in the drawing 20 has two openings 24 and 25, the opening 24 being central and constantly in communication with the inner extremity of an inlet passage 57 formed in the solid framework of the pump. The opening 25 of the valve is 25 elongated preferably to conform with the outer curvature of the valve, its area being substantially the same as that of the discharge port 19. During the rotary action of the valve, this opening 25 is successively 30 brought into communication with ports 26, 28 and 27 formed in the valve seat 7, these ports being respectively in communication with the cylinders 2, 3 and 4, through the medium of passages 29, 30 and 31, the extremities of these passages adjacent their respective cylinders being in register with ports 32, 33 and 34 formed in the bottoms of 35 the cylinders.

The bottom of the valve is preferably provided with a wearing plate or disk 35 which 40 may be secured thereto by means of suitable fastening devices passed through perforations 36. This wearing plate is provided with openings 37, 38 and 39, constructed 45 and arranged to register with the openings 25 and 24 and with the lower extremity of the port 19 of the valve respectively. The valve seat is also equipped with a similar wearing plate 40 which is detachably connected with the valve seat proper, by means 50 of suitable fastening devices passed through perforations 41. This wearing plate is also provided with openings 42, 43 and 44, and 55 58, arranged to register with the ports 26, 27 and 28, and the inner extremity of the passage 57, respectively, of the valve seat.

When the pump is in operation, the crank shaft 10 is rotated to cause the plungers to reciprocate in their respective cylinders, the 60 pitmen being connected with the cranks 9 of the shaft and properly spaced circumferentially according to the number of plungers and cylinders employed. With a pump having three cylinders, as illustrated in the drawing, the cranks would be spaced 120

degrees apart. The crank shaft is rotated to cause the valve 17 to rotate within its casing, it being assumed for the purposes of this specification, that the rotary action is in the direction of arrow *a*, in Fig. 2.

Assuming that the pump is in operation, and that the valve is in the position illustrated in Fig. 1, the plungers of the cylinders will be approximately in the positions shown, that is to say, the plunger of the 70 cylinder 2 will be descending and forcing the fluid therein through the passage 29, the port 19 and the chamber 45 within the housing 21 and out of said chamber through the outlet opening 23. At the same time, the piston of the cylinder 4 is moving upwardly 75 and the suction acts through the port 34, the passage 31, the valve seat port 28, the valve port 18 and the passage 57 to draw the fluid into the cylinder 4. The plunger 80 of the cylinder 3, it may be assumed, has just completed its downward stroke and commenced its upward movement, whereby fluid will be drawn thereinto through the port 27, since the opening 25 of the port 18 of the 85 valve overlaps the two ports 28 and 27 of the valve seat. In any event, the operation of the parts is so timed that the plungers operate in synchronism with the rotary action of the valve; and as there are three 90 plungers illustrated in the drawing and their cranks are spaced 120 degrees apart, two of the plungers must be moving downwardly or upwardly during the whole time except the instant that they are stopped at their upward or downward limit of movement to begin the stroke in the opposite direction. For this reason, both the suction and discharge ports of the valve are arranged to 95 overlap two ports of the valve seat during 100 the time that two plungers of the cylinders are moving in the same direction for either suction or discharge purposes.

While in the drawing, I have illustrated the cylinders as formed from an integral 110 casting, it is evident that they may be separately formed if desired and mounted in any other suitable manner. In order that the chambers of the cylinders may be fluid tight around the plungers, each cylinder is 115 provided with a stuffing box 46.

Having thus described my invention, what I claim is:

1. A valve mechanism comprising a seat having a plurality of ports, and a valve having a single suction port and a single discharge port, the valve being rotatable to bring its ports successively and alternately into communication with the ports of the valve seat in such a manner that one of said valve 120 ports always overlap two of the ports in the valve seat for the purpose set forth.

2. In a multiple plunger pump, the combination with the cylinders and plungers therein, of a rotary valve having a single 125

suction port and a single discharge port, a valve seat having ports in communication with the respective cylinders and means for operating the valve and plungers in properly timed relation whereby the ports of the valve are brought into communication with the ports of the valve seat in such a manner that either the suction or discharge port of the

valve always overlaps two of the valve seat ports.

In testimony whereof I affix my signature in presence of two witnesses.

GEORGE L. McDERMOTT.
